SAID MILLER ASSIGNOR TO J. LEWIS HOUGH, OF WILLIAMSPORT, PENNSYLVANIA.

HYDRANT.

1,083,291.

Specification of Letters Patent.

Patented Jan. 6, 1914.

Application filed June 8, 1908, Serial No. 437,304. Renewed May 27, 1912. Serial No. 700,117.

To all whom it may concern:

Be it known that we, FRANK J. MILLER and ROBERT H. THORNE, citizens of the United States, and residents of Williamsport, in the county of Lycoming and State of Pennsylvania, have made certain new and useful Improvements in Hydrants, of which the following is a specification.

This invention is an improvement in hydrants, of that class generally known as inside compression hydrants, and relates particularly to the means for draining the waste water from the hydrant when the main valve is closed; and the invention consists in certain novel constructions and combinations of parts as will be hereinafter described and claimed.

In the drawing, Figure 1 is a vertical longitudinal section of the lower portion of a hydrant embodying our invention. Fig. 2 is a cross section on about line 2—2 of Fig. 1. Fig. 3 is a longitudinal section of the upper portion of the hydrant, and Fig. 4 is an enlarged detail view of the drip valve lever, and the parts with which it operates.

By our invention we seek to provide a simple, durable, inexpensive and effective waste drip mechanism, all of the parts of which may be removed through the frost case.

In the construction shown, the frost case A fits at its lower end within the upwardly projecting flange B' on the base elbow B; such frost case and flange B' are provided with orifices *a* and *b* through which the waste discharged from the barrel C may pass. The barrel C fits within the frost case A at its upper end, as shown in Fig. 3, and at its lower end as shown in Fig. 1. The elbow B is provided at the base of the flange B' with the inwardly projecting horizontal annular flange B² receiving on its upper edge a packing B³ and threaded on its inner edge to receive the lower end of the valve chamber as presently described.

The valve chamber D has a cylindrical body portion D', is provided at its upper end with the outwardly projecting top flange D² bolted at D³ to the flange C' on the lower end of the barrel, and the lower end of the cylindrical body D' has a projecting threaded nipple D⁴ which screws into the flange B² at the top of the elbow B, and immediately above this threaded nipple is

provided the outwardly projecting annular flange D⁵ which bears upon the packing B³ and secures a tight joint between the parts B and D at the lower end of the latter, as shown in Fig. 1. The interior of the body D' at its lower end is formed at D⁶ into a valve seat for the main valve E which is fitted to said seat and is secured to the lower end of the main valve stem F, which latter may be suitably operated in a longitudinal direction by any well known means to open and close the main valve E, as will be understood by those skilled in the art.

By the described construction, it will be noticed we form the valve chamber separate from the barrel and the elbow, and make it detachable from the latter and to form a connection between the lower or base elbow and the barrel, and this valve chamber may be made of any suitable metal, and can be readily withdrawn through the frost case for repairs or for other desired purposes.

The valve chamber D is provided at one side with a valve seat G, preferably of bronze, opening into the space within the frost case, so the waste discharged through the valve seat G may pass out of the openings *a* *b*, and the seat G as shown is preferably provided with a separate tube inserted in the side of the chamber D and projecting within said chamber in position to receive the drip valve H' which is carried on a rocking lever H arranged for operation as presently described.

For supporting the drip lever H, we provide the valve chamber D with an arch I, extending from side to side of the valve chamber at the upper end of the latter, provided centrally with a box or hub I', to receive the main valve stem F, and slotted 90 radially at I² on one side of the hub to receive the drip valve lever H, which is pivoted midway between its ends at H² within the slot I² as shown in Figs. 1 and 2 of the drawing. This drip valve lever extends 95 alongside the main valve stem F, and is provided on its side adjacent to said stem with inwardly projecting portions *h* and *h'*, respectively, above and below the pivot H² of the valve lever H. These projections *h* and *h'* are preferably inclined as shown in Fig. 1, and are arranged for engagement by the shoulders *f* and *f'*, on the valve stem, such shoulders *f* and *f'* being preferably the upper and lower ends of a plate *f*² 110

secured to the side of the stem F and operating therewith through the hub I' of the arch I and arranged above and below the said hub to operate upon their respective 5 projections on the drip valve lever. By having the arch slotted to receive the drip valve, the height of the arch is reduced, thereby increasing the waterway. It is manifest that by pivoting the drip valve 10 lever to the arch we are able to arrange the said lever partly below and partly above the arch thus reducing the height of the arch as compared to a construction in which the lever is supported and arranged entirely below the arch. It will also be noticed 15 by the construction of the central hub I' with a hole through which the main valve stem passes, and of a shape corresponding to the said main valve stem, together with 20 the plate f², and preferably in the form of an oblong square, we provide for operating the drip valve, and at the same time prevent the parts from being put together in any way but the correct one.

25 The drip valve H is preferably recessed and fitted with packing H⁴ held in place by a screw or rivet H⁵ and fitted to the valve seat G, as will be understood from the drawing.

30 In operation it will be noticed that when the main valve stem is moved upward to close the main valve E, the shoulder f engaging with the projection h on the drip valve lever will operate the same to the 35 position shown in Fig. 1, and as the main valve E is closed, the waste or drip valve will be opened so that the barrel may be drained as desired. On the other hand, as the valve stem F is lowered to open the 40 valve E, the lower shoulder f' engaging the lower projection h' of the drip valve lever will close the drip valve H against its seat G, and thus shut off the passage of waste through the drip valve when the main valve 45 is open. This operation, it will be noticed, is positive in both the opening and closing of the main valve, and is effected in a simple manner and by a mechanism which possesses no parts likely to get out of order.

50 We claim:

1. The combination substantially as herein described, of a base elbow, a main valve chamber threaded at its lower end into connection with the base elbow and provided 55 with a lateral flange overlying the base elbow, and with packing between the said flange and elbow, and also having at its upper end an external lateral flange and provided internally with a cross arch having 60 a central hub having an opening for the valve stem and slotted radially on one side of the hub for a drip valve lever, the said valve chamber being provided below the 65 said arch with a lateral waste opening, a drip valve lever passing through a slot in

the arch and pivoted between its ends thereto and provided above and below the said arch with inwardly projecting portions and having below the arch a valve for controlling the waste opening in the valve chamber, 70 a main valve, a main valve stem operating through the arch and having upper and lower shoulders for operative engagement with the upper and lower projections of the drip valve lever, and a barrel secured to the 75 laterally projecting flange at the top of the valve chamber, substantially as set forth.

2. The combination of a main valve, a pivoted drip valve lever having, above and below its pivot, portions for engagement by 80 operating means, and a main valve stem having means between and operating against said portions of the drip valve lever to operate the same positively to both open and shut the drip valve and an arch to which 85 said valve lever is pivoted between its ends.

3. The combination of an elbow, a valve chamber secured thereto and having a cross arch provided with a central hub for a main valve stem, and also having a lateral drip 90 waste opening, a drip valve lever pivoted to the arch and having a valve controlling the drip waste opening, a main valve, a main valve stem, and means on the latter for operating the drip valve lever, substantially 95 as set forth.

4. The combination of a main valve, its stem, a casing having a lateral drip waste opening, and a cross arch provided with a central hub for the main valve stem, the 100 latter having shoulders above and below the arch, and a drip valve lever pivoted between its ends to the arch and having above and below the arch inwardly projecting portions for operative engagement by the shoulders 105 on the main valve stem, substantially as set forth.

5. In a hydrant, the combination of a barrel flanged at its lower end, a base elbow having the upwardly projecting flange, a 110 frost case fitting at its lower end within the upwardly projecting flange of the best elbow, the valve chamber having the upper flange bolted to the lower end of the barrel and having its lower end screwed into the 115 base elbow, the said valve chamber having a lateral drip waste opening, and an arch extending from side to side of said chamber above the drip waste opening and provided with a central hub, having a non-circular 120 opening, and a drip valve lever pivoted to the arch and controlling the drip waste opening in the valve chamber, the main valve and the main valve stem fitting the non-circular opening in the arch and having above and 125 below the arch means for operating the drip valve lever, substantially as set forth.

6. The combination of a base elbow, a barrel, a valve chamber secured at its lower end to the base elbow and at its upper end to the 130

- barrel, and provided with a drip waste opening and above the same with a cross arch having a non-circular opening for the main valve stem, a drip valve lever pivoted between its ends to the arch, and having above and below the same inwardly projecting portions, a main valve and a plate secured thereto and operating therewith within the non-circular opening of the arch, and arranged at its upper and lower ends to positively operate the drip valve lever, substantially as set forth. 35
- 5 7. The combination of a base elbow, a barrel, a valve chamber secured at its opposite ends to said barrel and elbow and provided with a drip waste opening and with a cross arch having a central non-circular opening for a main valve stem, and also slotted radially for a drip valve lever, a 15
- 10 drip valve lever fitting and pivoted within the said recess and projecting above and below the arch, a main valve and a main valve stem fitting in the non-circular opening of the arch and shouldered above and below 20
- 15 the arch whereby to positively operate the drip valve lever, substantially as set forth.
- 25 8. The combination of a barrel, a base elbow, a valve chamber connecting the said elbow and barrel and having a lateral drip waste opening, and a cross arch having a central non-circular opening for a main valve stem, a main valve, the main valve stem operating in the non-circular opening of the arch, and provided above and below 30
- 20 the arch with shoulders for operating a drip valve lever, and a drip valve lever pivoted between its ends to the arch and having above and below the arch inwardly projecting arms for engagement with the shoulders of the main valve stem, substantially as set forth. 35
- 25 9. The combination substantially as herein described, of a main valve chamber, a cross arch, a main valve stem operating through the arch, a drip valve lever pivoted between its ends to the arch, and provided above and below the said arch with inwardly projecting portions and also having below the arch a drip valve, and upper and lower shoulders on the main valve stem engaging with the upper and lower portions of the drip valve lever, substantially as set forth. 40
- 30 10. The combination in an apparatus substantially as described, of a main valve, a seat therefor, a cross arch above the said valve seat, a drip valve lever pivoted to the said arch and having a valve below its pivot and between the said arch and the seat for the main valve, a main valve stem movable longitudinally through the arch, and means whereby such movement of the valve stem 45
- 35 may operate the drip valve lever. 50
